United States Patent Office

Des. 190,224
Patented May 2, 1961

190,224

SERVICE STATION BUILDING

Richard C. Beach, 1322 Modiste, and Charles B. Popkin,
7813 Nairn, both of Houston, Tex.

Filed Jan. 25, 1960, Ser. No. 59,149

Term of patent 14 years

(Cl. D13—1)

Figure 1 is a front perspective of a service station building, showing our new design.

Figure 2 is a top plan view of the building; and,
Figure 3 is a horizontal section of the building.

The rear of the building is plain in appearance.
We claim:

The ornamental design for a service station building,
as shown and described.
